UNITED STATES PATENT OFFICE.

ROBERT J. WILLIAMS, OF CINCINNATI, OHIO.

WINDOW-CLEANER.

No. 820,688.

Specification of Letters Patent.

Patented May 15, 1906.

Application filed October 26, 1905. Serial No. 284,439.

To all whom it may concern:

Be it known that I, ROBERT J. WILLIAMS, a citizen of the United States, residing at Lafayette and Adams streets, Norwood, Cincinnati, in the county of Hamilton and State of Ohio, (whose post-office address is Lafayette and Adams streets, Norwood, Cincinnati, Hamilton county, Ohio,) have invented certain new and useful Improvements in Window-Cleaners, of which the following is a specification.

My invention relates to improvements in window-cleaners designed for cleaning the window-panes of locomotive-cabs, pilot-cabs, or electric-car cabs, and for any window-pane in any vehicle where it is desired to clean both sides of the window-pane from the inside.

The objects of my invention are, first, to provide a simple, cheap, practical window-cleaner; second, to provide a window-cleaner free from complicated mechanism and accurate in its operation; third, to make a window-cleaner possessing these elements of cheapness and practicability which will operate to remove all atmospheric condensation, snow, sleet, rain, or moisture of whatever kind and to do so perfectly over the portion of the pane traversed and to clean both the inner and outer sides simultaneously; fourth, to make a window-cleaner in the construction of which the openings and crevices will not permit the entrance of cinders, dust, and other objectionable matter. I attain these objects by the construction of a window-cleaner as illustrated in the accompanying drawings, in which—

Figure 1 shows the window-pane, the sash, and the window-cleaner in perspective. Fig. 2 shows the window-cleaner at the top of the window, where it is held when not in use, and with it a perspective view of the window and sash. Fig. 3 shows a vertical section on line xx in Fig. 2. Fig. 4 shows a sectional view of Fig. 2 on line yy , hereinafter more fully described. Fig. 5 is a cross-sectional view of the cross-head on line zz in Fig. 1 elevated on a side position hereinafter more fully described.

Like numerals refer to like parts throughout the several views.

In Fig. 1, 1 designates the sash of the window-pane 2. The two vertical sash-rails 1 have a lengthwise slotted portion, as indicated by 3. This slot 3 passes entirely through the vertical sash-rails and permits the movement of the cross-head 6, attached to movable blocks

at either end thereof, to which blocks are fastened the ends of cross-heads 6. To cross-heads 6 are attached suitable strips 4 of sufficient width to cover slot 3 and long enough to cover said slot 3 its entire length when the window-cleaner is recumbent at the top. 55 designates grooves in which strips 4 move downwardly in the act of bringing the cleaner downwardly. Grooves 5 extend down in a central portion of the vertical sash-rails and serve the purpose not only to guide the cross-head 6 smoothly, but they serve also as coverings for slots 3 to prevent the ingress of dust, dirt, and cinders in the otherwise open slots when the cleaner is at the top of the window-pane 2. It will be apparent here that when the cleaner is "down" there will necessarily be two apertures in the window-sash—one in each vertical sash-rail—open; 75 but when the cleaner is raised it carries with it strips 4, the top ends of which are permanently fastened to cross-head 6. Hence the long protruding covering-strips 4 thereby close the apertures against ingress of any 80 dust or dirt. It is further apparent that the cleaner is designed to clean the upper three-fifths of the area of the pane and is never drawn over the entire area thereof. 66 designates a double cross-head, supplied on the inner and outer side with any suitable absorbent, as 85 felt or a rubber eraser, which contacts closely with the pane. 77 indicate the position of this eraser, of which there is one to contact each the inside and outside of the pane simultaneously.

8 indicates a handle-knob which is attached to a pin inserted on the inside cross-head, and the knob is encircled by clasp 9, which is preferably made of spring-steel fastened in the middle to top sash and adapted to engage pin 8 and to hold the cleaner merely by fitting closely around it, but may be easily disengaged.

I am aware that slight modifications in construction may be made without injury to the utility of my invention. Hence I do not desire to be restricted to this precise construction.

Having thus fully described my invention, what I claim as new, and desire to secure by Letters Patent, is—

In a window-cleaner of the class described, a window-sash each of the side rails whereof is provided with a slot and with grooves forming a continuation of said slot, cross-heads on each side of window, wipers on said

cross-heads, cross-head connecting-blocks reciprocal in said slots, strips on said blocks and cross-heads and reciprocal in said slots and grooves, a handle on one of said cross-heads, and means to hold the strips and cross-heads in an elevated position when not in use, substantially as described and for the purposes set forth.

In testimony whereof I have signed my name to this specification in the presence of 10 two subscribing witnesses.

ROBERT J. WILLIAMS.
